(57) **CLAIM**

The ornamental design for a handle for surgical device, as shown and described.

DESCRIPTION

FIG. 1 is a front, top, left-side perspective view of a handle for surgical device, showing the new design;

FIG. 2 is a front, top, right-side perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines in the drawings illustrate portions of the handle for surgical device that form no part of the claimed design.
